BAND-SPREADING TUNING DEVICE

Joseph F. Riley, Chicago, Ill., assignor to Howard
Radio Company, Chicago, Ill., a corporation of
Illinois

Application August 13, 1934, Serial No. 739,667

18 Claims. (Cl. 116—124.1)

This invention relates to tuning devices for radio receivers, and more particularly to such a device wherein band-spreading is achieved.

One feature of this invention is that it permits conventional tuning throughout the broadcast band; another feature of this invention is that it permits band spreading in the particular bands of the radio spectrum in which that is desirable; still another feature of this invention is 10 that it combines two indicators on one dial, said indicators showing conventional operation and band spreading operation, respectively; yet another feature of this invention is that when the band spreading mechanism is operative station 15 settings are spaced much farther apart on the dial than during conventional operation; another feature of this invention is that it eliminates additional condensers; other features and advantages of this invention will be apparent from the following specification and the claims, in which—

Figure 1 is a front elevation of the dial and manual operating means; Fig. 2 is a sectional view along the line 2—2 of Fig. 1.

It has long been considered necessary to 25 achieve band-spreading action in certain points of the frequency spectrum, and more particularly in the short wave bands. In all wave sets, the principal condenser or gang of condensers must have sufficient maximum capacity to tune 30 throughout the broadcast range. This capacity is so large that where the same condensers are used in connection with short wave reception in the set, a very small rotation of the rotor plates results in a large change in frequency. This 35 large change of frequency per degree of rotation results in certain defects as, for example, the fact that weaker stations are passed over completely, and resonance with the carrier band of the desired station is much more difficult to attain, 40 especially in the hands of an inexperienced operator. Various methods of reducing the effective change in capacity for a given rotation of a manual operating means have been known. Most of these methods, however, are electrical in character, requiring a separate variable condenser of 45 smaller capacity, or a separate fixed condenser adapted to be placed in circuit with the main condenser. This invention enables the main condenser to be used throughout all the bands of 50 the desired spectrum, and provides a conventional manual drive for use in the longer wave lengths, and a much lower geared drive for use where band-spreading is desired. This invention also provides two separate indicators cooperating on 55 one dial, thus enabling normal operation and

band-spreading operation to be indicated on the one dial.

In the particular embodiment of the invention illustrated herewith, a panel 10 has mounted thereon a dial 11 having an outer calibrated portion 12 and an inner calibrated portion 13. Concentrically mounted in relation thereto are two indicator needles, a main indicator 14 and a band-spreading indicator 15. This dial may be protected by a transparent covering, as the celluloid sheet 16.

The main tuning condenser 17 has projecting therefrom a rotatable member or shaft 18 by which it is driven, this shaft projecting through the center of the dial 11 and having the indicator 15 rigidly mounted thereon, as by a set screw 19. Surrounding the shaft 18 at its outer extremity, and passing through the dial 11 is an annular member or intermediate transmission member 20. This intermediate member is freely 20 rotatable both with respect to the shaft and to the dial, and has the indicator 15 rigidly mounted thereon at its outer extremity.

Immediately below the dial, a shaft 21 is provided, this shaft extending without the panel 10 25 and having on its outer end a manually operating knob 22, which knob is removably fastened thereto, as by a set screw 23. The shaft 21 is supported at its inner end by a bearing 24 mounted on the chassis 25 of the receiving set, and at its 30 outer end by a sleeve 26. The sleeve 26 extends through the panel 10, and has at its outer end, a second manual operating knob 27 attached thereto, as by a set screw 28. This sleeve 26 is adapted to rotate and to have free longitudinal 35 movement, both with respect to the shaft 21 and to the panel 10.

The shaft 21 has rigidly mounted thereon a small friction disk 29 engaging a larger friction disk 30 at the point 31, said larger friction disk 40 being rigidly attached to the shaft 18, as by a set screw 32. In the particular embodiment illustrated here, a ratio of about 6 to 1 is obtained by the use of these two friction disks 29 and 30. Conventional or normal operation of the main 45 condenser shaft 18 is obtained through manual rotation of the knob 22. Rotation of the knob 22 drives the disk 29 through the shaft 21, effects rotation of the disk 30, and thus tunes the set through rotation of the main condenser.

The sleeve 26 has rigidly attached thereto a friction disk 33 which disk cooperates with a larger friction disk 34 through frictional contact at the point 35. This larger disk 34 is rigidly mounted on the intermediate transmission mem- 50 55

ber 20. The intermediate transmission member 20 has also rigidly mounted thereon a small friction disk 36 adapted to rotate a large friction disk 37 through contact therewith at the point 38. 5 This large disk 37 is mounted on the sleeve 26 and is freely rotatable with respect thereto. The disk 37 has rigidly attached thereto spring grip members or clips 39 adapted to yieldingly engage a clutch member 40 rigidly mounted on the shaft 10 21. The disk 37 and its clips 39, although freely rotatable with respect to the sleeve 26, are so mounted thereon that longitudinal movement of the sleeve effects a similar movement of the clips 39. Manually achieved longitudinal movement of 15 the sleeve 26 thus serves to force the clips 39 into engagement with the clutch member 40, or to disengage them therefrom.

When conventional operation is desired, the mechanism is in the position illustrated in Fig. 2. 20 It will be noted that the clips 39 are disengaged from the clutch member 40 and rotation of the knob 27 will have no effect thereon. In this position, rotation of the condenser is achieved through manual operation of the knob 22 which 25 transmits motion through the shaft 21, the disk 29, the disk 30 and the shaft 18 to the condenser plates. When the mechanism is in this position, the indicator 14 revolves upon operation of the knob 22, and indicates the relative setting of the 30 condenser plates. The indicator 15, however, does not revolve since no motion is being transmitted to the intermediate member 20. When band-spreading is desired, the knob 27 is pushed in closer to the panel 10, which motion is transmitted by the sleeve 26 to the clips 39 and achieves 35 engagement between them and the clutch member 40. Rotation of the knob 27 is then transmitted through the sleeve 26, the small disk 33 and the large disk 34 to the intermediate member 40 40 20. Since the intermediate member 20 is now in operation, the smaller indicator 15 will revolve, and thus indicate that the band-spreading mechanism is in operation. From the intermediate member 20 the drive will be transmitted 45 through the small disk 36, the large disk 37 and the clips 39 to the clutch member 40, whereby rotation of the shaft 21 will be effected. Rotation of the shaft 21 again drives the condenser shaft 18 through the medium of the small disk 50 29 and the large disk 30. It will be noted that when the band-spreading mechanism is operated, a triple reduction is achieved in the drive between the knob 27 and the condenser shaft 18. One reduction is achieved by the disks 33 and 34, another by the disks 36 and 37, and the third by the disks 29 and 30. A very low ratio of manual 55 movement to condenser movement is thus achieved, resulting in a band-spreading effect. Since the indicator 15 is mounted on the intermediate member, and not on the condenser shaft 18, the condenser shaft rotates at a reduced ratio 60 with respect to the rotation of the indicator 15. This reduced ratio is achieved through the second and third reduction means in this particular 65 embodiment.

The dial 11 may have its outer portion calibrated arbitrarily, by kilocycles, or by wavelength. In any event, certain bands of the spectrum will be found on certain portions of this dial. 70 Should a listener desire to tune in on stations in the 49 meter band, for example, he would, through use of the manual knob 22, set the main indicator 14 to a position on the dial corresponding to the approximate center of the 49 meter band. He 75 would then push in the knob 27 and tune there-

after with that knob, thus achieving a band-spreading action indicated on the inner portion of the dial by the small indicator 15. Since it is desirable that the band-spreading action be effective both above and below the initial setting of 5 the indicator 14, it is preferable that the small indicator 15 be set at approximately the center of its scale before the clutch means is engaged through the pushing in of the knob 27. When it is desired to return to conventional operation, or 10 to shift to another band in the spectrum, the knob 27 is pulled out and operation is achieved through the use of the conventional knob 22.

In the particular embodiment of the invention illustrated herewith the friction disks 34 and 37 15 are sufficiently flexible that the sleeve 26 may be moved longitudinally to effect engagement of the clips 39 with the clutch means 40 without in any way detrimentally affecting the operativeness of the reduction drive operating through 20 those disks.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of 30 the prior art.

What I regard as new, and desire to secure by Letters Patent, is:

1. A tuning device for radio receivers, including; a rotatable member; a manual drive therefor; a second manual drive therefor, said second drive having a lower ratio than said first drive; a dial; and two indicators concentrically arranged on said dial indicating said two drives respectively. 40

2. A tuning device for radio receivers, including; a rotatable member; a manual drive therefor; a second manual drive therefor, said second drive having a lower ratio than said first drive; a dial; two indicators concentrically arranged on said dial indicating said two drives respectively; and means whereby one of said drives may be manually engaged or disengaged. 45

3. A tuning device for radio receivers, including; a shaft; a manual drive therefor; a second manual drive operating through an intermediate transmission member on said shaft; a dial concentrically arranged with respect to said shaft; an indicator on said shaft adjacent said dial; and a second indicator on said intermediate transmission member adjacent said dial. 50

4. Apparatus as claimed in claim 3 including means whereby one of said drives may be manually engaged or disengaged.

5. A tuning device for radio receivers, including; a shaft; indicating means comprising a dial concentric with said shaft and an indicator mounted on said shaft adjacent said dial; selectively engageable manually operable means for rotating said shaft and indicator or for rotating said shaft at a reduced speed; a second indicator to indicate the reduced speed rotation, said rotating means when rotating the shaft at a reduced speed operating said second indicator at a faster speed than said shaft. 60

6. A tuning device for radio receivers, including; a shaft; indicating means in connection with said shaft; a second indicating means; manually operable means whereby said shaft may be rotated; a second manually operable 70 75

means; reduction-drive means; and clutch means whereby said second manually operable means is engaged through said reduction-drive means to said shaft.

5 7. Apparatus as claimed in claim 6 wherein said shaft is rotated at a reduced speed with respect to said second indicating means.

8. A tuning device for radio receivers, including; a rotatable member; a dial concentric therewith; means for rotating said rotatable member; an indicator adjacent said dial showing the rotation of said rotatable member; a second indicator concentrically mounted on said dial, said indicator being stationary when said means is 10 operative; and means whereby said second indicator may be rotated and said member may be simultaneously rotated at a reduced speed with respect to said second indicator.

9. A tuning device for radio receivers, including; a rotatable member; a dial concentric therewith; manual means for rotating said rotatable member; an indicator mounted on said member adjacent said dial; a second indicator concentrically mounted on said dial, said indicator being stationary when said means is 15 operative; and means for rotating said second indicator whereby said member is rotated at a reduced speed with respect to said second indicator.

30 10. A tuning device for radio receivers, including; a shaft, a dial concentric therewith; an indicator mounted on said shaft adjacent said dial; an annular member concentrically mounted with respect to said shaft; a second indicator on said member; manually operable driving means whereby said shaft may be rotated; and a second manually operable driving means for rotating said annular member whereby said shaft is rotated at a reduced speed with respect to said second indicator.

40 11. A tuning device for radio receivers, including; a shaft; a dial concentric therewith; an indicator mounted on said shaft adjacent said dial; an annular member journalled on said shaft; a second indicator mounted on said member and concentric with said dial; manually operable reduction-drive means whereby said shaft may be rotated; a second manually operable reduction-drive means whereby said annular member is 45 rotated; and means whereby rotation of said annular member rotates said shaft at a reduced speed with respect thereto.

50 12. A tuning device for radio receivers, including; a shaft; a dial concentric therewith; an indicator mounted on said shaft adjacent said dial; an annular member journalled on said shaft; a second indicator mounted on said member;

manually operable reduction-drive means whereby said shaft may be rotated, said means including a second shaft; a manually rotatable sleeve journalled on said second shaft; driving means connecting said annular member to said sleeve; 5 and clutch means whereby rotation of said annular member, when said clutch is engaged, effects a rotation of said first mentioned shaft at a reduced speed with respect to said annular member.

10 13. Apparatus as claimed in claim 12 wherein said sleeve is slidably journalled on said second shaft whereby longitudinal movement of said sleeve effects engagement of said clutch means.

14. Apparatus as claimed in claim 12 wherein 15 said sleeve is slidably journalled on said second shaft whereby longitudinal movement of said sleeve effects engagement of said clutch means, and wherein said driving means comprises continuously engaged friction disks. 20

15. A tuning device for radio receivers, including; a rotatable shaft; a dial concentric therewith; an indicator mounted on said shaft adjacent said dial; manual means for rotating said shaft; an annular member rotatably mounted on 25 said shaft; an indicator mounted on said annular member adjacent said dial; transmission means for connecting said annular member and shaft whereby rotation of the annular member will rotate the shaft at a reduced speed; and 30 means for rotating the annular member.

16. A tuning device for radio receivers, including; a rotatable shaft; a dial concentric therewith; an indicator mounted on said shaft adjacent said dial; a second shaft; manual means 35 for rotating said second shaft; transmission means connecting said shafts; an annular member rotatably mounted on said first shaft; an indicator mounted on said annular member adjacent said dial; transmission means connect- 40 ing said annular member to said first shaft, whereby rotation of the annular member will rotate said first shaft at a reduced speed; a sleeve rotatably mounted on the second shaft; manual means for rotating said sleeve; and transmission 45 means connecting said sleeve and annular member.

17. Apparatus as claimed in claim 16 in which the transmission means connecting the annular member and the first shaft includes a clutch. 50

18. Apparatus as claimed in claim 16 in which the transmission means connecting the annular member and the first shaft includes the transmission means connecting the first and second shafts. 55

JOSEPH F. RILEY.
